UNITED STATES PATENT OFFICE.

FRANK J. KRISTOFEK, OF ST. PAUL, MINNESOTA, ASSIGNOR TO BROWN & BIGELOW,
OF ST. PAUL, MINNESOTA, A CORPORATION OF MINNESOTA.

HANDY PAD.

Application filed December 20, 1920. Serial No. 431,984.

To all whom it may concern:

Be it known that I, FRANK J. KRISTOFEK, a citizen of the United States, residing at St. Paul, in the county of Ramsey and State 5 of Minnesota, have invented a new and useful Improvement in Handy Pads, of which the following is a specification.

My invention relates to a handy pad including a receptacle for holding a pad of 10 loose sheets of paper wherein the sheets are freely removable as desired. A cover is hinged to the receptacle in a manner to adjust itself at an inclined angle when the same is open and to cover the major portion 15 of the receptacle when closed.

My invention includes resilient means to hold or adjust the leaves of the pad into a position so that they can be easily engaged and removed to be used for memorandum or 20 other purposes as may be desired. The resilient adjusting means elevates the forward end of the pad against stops which prevent the sheets from projecting out of the receptacle when the same is open, while the front 25 wall of the receptacle is cut away to provide a finger opening. This construction allows the last sheet of the pad to be removed as readily as the first.

The inner surface of this cover is adapted 30 to form a display means upon which a pocket may be provided to support a calendar pad in a manner so that when the cover is in closed position the pocket projects into the receptacle, to allow the cover to fold 35 against the upper edges of the same to lie in a plane parallel to the bottom.

The cover is provided with attaching ears 40 formed integral therewith which project from the side and end so as to hingedly attach the cover to the receptacle body in a manner to cause the attached end of the cover to engage the upper surface of the receptacle to support the cover in a backwardly inclined angle, when the free end of the 45 cover is raised into open position. In this manner the cover is supported similar to an easel so as to readily display the inner surface thereof together with a calendar or other display matter attached thereto. This 50 construction allows the handy pad to be folded into a small compact state for shipping and to form an attractive display when open.

In the drawings forming a part of this 55 specification:

Figure 1 is a perspective view of the handy pad in open position, ready for use.

Figure 2 is a perspective of the same in closed position, illustrating the compactness 60 of the pad when folded.

Figure 3 is a cross section of the pad in closed position.

Figure 4 is a central cross section of the same in open position.

Figure 5 is a bottom view of the same.

Figure 6 is a central cross section of an alternative construction:

The handy pad A is composed of a receptacle or container B having a general rectangular shape in which a pad C of loose 70 sheets 10 is held collectively. The receptacle B is formed of thin sheet material of any suitable nature.

The handy pad A is adapted to be supported by suitable corner members 11 which 75 form legs or supports for the receptacle and act as braces for the corners of the same. The supporting members or legs 11 are rigidly secured by spot-welding or other suitable means to the body of the receptacle B. 80

The pad C is held in the receptacle with the leaves or sheets 10 freely disposed so that they can be removed separately. The front wall 12 and the bottom 13 of the receptacle are cut away centrally to form a recess 14 85 at the front so the sheets can be easily engaged with the fingers to remove them from the receptacle C.

Spring fingers 15 are cut from the body 90 of the bottom 13 of the receptacle B and are bent to project upwardly so as to tend to force or hold the forward ends of the sheets 10 upward against the stops 16. The stops 16 are formed integral with the sides 17 and project inward from the forward upper 95 edges of the same. As the sheets are used from the pad C and the size of the pad diminishes the spring fingers 15 force the remaining sheets in the receptacle upward against the shoulders or stops 16 and the recess 14 allows the remaining sheets to be removed individually or collectively very easily.

A cover D is hingedly secured to the sides 17 by means of the attaching ears 18 in a 105 manner to cause the rear edge 19 of the cover to engage against the upper edges 20 of the sides 17, forming a shoulder to limit the backward movement of the free end 21 of the cover D. The ears 18 project down- 110

ward and away from the edge 19 to permit the cover to be raised and moved into a backwardly inclining angle in relation to the receptacle B before the edge 19 engages the edges 20. This construction permits the cover D to be secured by suitable eyelets 22 with the ears 18 overlapping the outer surface of the sides 17 and permits the opening of the cover without binding on the receptacle. To have the cover positioned in a manner that its rear edge 19 engages the upper edge 20 of the receptacle when it is in a backwardly inclining position as illustrated in Figure 1, it is essential that the ears 18 be secured to the sides a short distance from the rear wall 23 of the receptacle. This construction leaves an open space 24 between the edge 19 and the upper edge of the rear wall 23 when the receptacle B is closed as illustrated in Figure 3. This space can be closed by a suitable horizontally extending wall 25 projecting from the back 23 as is illustrated in the construction shown in Figure 6. When thus constructed the receptacle is adapted to conceal the sheets of the pad C leaving only the front edges exposed through the opening 14.

The cover D forms a suitable display easel for a calendar or display which is held by the pocket 26 to the inner surface of the cover. A suitable form of perpetual calendar may be supported by the pocket 26. When the cover D is moved into closed position as illustrated in Figure 3, the pocket 26 projects into the receptacle and is concealed with the calendar in a manner to provide a compact receptacle for containing the pad and display matter.

The simple inexpensive construction of the handy pad A, together with the easy manner in which it can be closed by the cover to a compact state makes it easy to pack for storing or shipment, which is an essential feature to make up a practical device of this nature. The handy pad is particularly adapted for use on a desk to provide a pad of loose sheets which can be used for memorandum purposes and where a pad of this kind is used it is very essential to have a calendar associated therewith so as to be able to readily refer to the same, while if at any time the user wishes to cover the sheets to protect the same, this can be readily be accomplished by dropping the cover into closed position.

In accordance with the patent statutes, I have described the principles of operation

of my invention, together with the apparatus which I now consider to represent the best embodiment thereof, but I desire to have it understood that the construction shown is only illustrative and that the invention can be carried out by other means and applied to uses other than those above set forth within the scope of the following claims.

What I claim is:

1. A handy pad comprising a receptacle adapted to collectively support a pad of memorandum sheets and a cover hingedly secured by integral depending ears to the sides of the same in a manner to cause the attached edge of said cover to engage the upper edge of said receptacle to form a shoulder for supporting said cover at an angle in relation to said receptacle when the same is open.

2. In an article of the class described, a container adapted to hold a pad of sheets, a shoulder formed near the forward upper edge of the container, spring means inclined from the back to the front and formed from the bottom of said container adapted to press the forward end of the pad in said container against said shoulder, a cover adapted to close said container and an opening adapted to expose the forward elevated end of the pad in the container whereby the sheets of the same can be easily engaged and removed therefrom.

3. A handy pad comprising a container having a pad of loose sheets, shoulders adapted to engage the upper sheet of the pad in said container to prevent the forward upper edge of the pad from projecting out of the same, an inclined resilient means formed integral with the bottom of said receptacle adapted to incline from the back toward the front and positioned within said container in a manner to hold the front ends of the sheets of the pad against said shoulders and to position the pad at an incline within said receptacle.

4. A handy pad including a series of loose memorandum sheets, a container adapted to hold said sheets collectively, a cover secured to the sides of said container in a manner to be supported at an angle by engaging with the upper surface of said container when in open position and means for supporting a calendar pad to the inner surface of said cover.

St. Paul, Minnesota, November 4th, 1920.

FRANK J. KRISTOFEK.
